Primary Examiner—Ruth McInroy*Attorney, Agent, or Firm*—Dickinson Wright PLLC[57] **CLAIM**

A new original design for a cellular site antenna pole, as shown and described.

DESCRIPTION

FIG. 1 is an elevational view of a first embodiment of the cellular site antenna pole showing my new design, the design having rotational symmetry;

FIG. 2 is a top view thereof;

FIG. 3 is an elevational view of a second embodiment thereof, the design having rotational symmetry;

FIG. 4 is a top view of the second embodiment;

FIG. 5 is an elevational view of a third embodiment thereof, the design having rotational symmetry, the top view thereof being the same as that shown in FIG. 2; and,

FIG. 6 is an elevational view of a fourth embodiment thereof, the design having rotational symmetry, the top view thereof being the same as that shown in FIG. 4.

The phantom lines of the base portion of the cellular site antenna pole embodiments shown in FIGS. 5 and 6 are for illustrative purposes only and form no part of the claimed design.
